HOLDER

Murray Margo, Hawthorne, Calif.

Application August 19, 1944, Serial No. 550,187

4 Claims. (Cl. 242—55.2)

1

This invention has to do with a holder and has particular reference to a holder for handling articles such as soap, toilet paper, and the like. It is a general object of the invention to provide a holder for articles such as those mentioned, which is simple and inexpensive of manufacture and also highly efficient and convenient to use.

The invention has to do, generally, with improvements in holders of the type wherein a pair of opposed pivoted arms are related to engage and hold an article between them by reason of the action of gravity on the arms and on the article itself.

In accordance with my present invention I provide a simple, effective coupling or linkage between a pair of gripping arms so that the arms work in synchronism and are maintained in true alignment or in truly opposed relation one to the other.

It is another object of this invention to provide a holder of the general character referred to involving a very simple and effective means normally yieldingly urging the arms in or together to maintain them in gripping engagement with an article arranged between them. The present invention provides a simple, helical spring coupled in the mechanism so it acts in a most advantageous manner.

It is another object of this invention to provide a holder of the general character referred to in which the gripping arms are provided at their outer ends with heads shaped to engage and center a roll of paper, or the like, between the arms.

A further object of the invention is to provide improvements in means for stopping or limiting the pivotal movement of the arms in a holder such as I have referred to.

The various objects and features of my invention will be fully understood from the following detailed description of typical preferred forms and applications of the invention, throughout which description reference is made to the accompanying drawings, in which:

Fig. 1 is a front or face view of a holder embodying the invention showing gripping arms of a type and design suitable for engaging and holding soap, or the like. Fig. 2 is a plan view of the holder showing the general configuration of the arms. Fig. 3 is a back or rear view of the holder, being a view taken substantially as indicated by line 3—3 on Fig. 2. Fig. 4 is an enlarged detailed sectional view taken as indicated by line 4—4 on Fig. 3. Fig. 5 is a reduced view similar to Fig. 1 showing the holder applied to a support such as a wall and showing a cake of soap held therein.

2

Fig. 6 is a view similar to Fig. 1 showing a form of the invention having arms for holding a roll of toilet paper or the like. Fig. 7 is a plan view of the holder shown in Fig. 6 showing a roll of toilet paper held in the device. Fig. 8 is a rear view of the device, being a view taken as indicated by line 8—8 on Fig. 7, and Fig. 9 is a detailed sectional view taken as indicated by line 9—9 on Fig. 6.

10 The present invention provides improved features of construction for a holder of the general type which is the subject of my issued Patent No. 2,153,840, issued April 11, 1939. In practice the improvements which I provide are applicable to holders for toilet paper, soap, or other articles. In the drawings I have shown in Figs. 1 to 5 a holder designed primarily to handle soap, or the like. It will be apparent from the following description that certain features of construction may be varied in order to adapt the holder to special uses, whereas there are other features of construction common to the two forms shown and which are applicable, generally, to holders of the general type referred to.

15 Referring in particular to the form of the invention shown in Fig. 1 the device involves, generally, a base 10, a pair of arms 11, pivotal mounting means 12 for the arms, means 13 coupling the arms so they work in synchronism, and other details or features such as means normally yieldingly urging the arms toward each other, stop means for the arms, etc.

The base 10 of the holder serves as a mounting or frame for the various other parts of the device and is intended to be applied to a wall or other like support. In practice it is desirable to make the base plain and compact, for example, I preferably form it so that it has a flat, rectangular front 14 and a rearwardly extending flange 15 projecting from the marginal portion of the front. The flange 15 extends far enough rearward of the front 14 so that a suitable chamber or cavity 16 is established in the base when the base is applied to a support such as a wall W. In the drawings I have shown a pair of openings 17 provided in the front 14 of the base designed to pass mounting screws. In the case illustrated the outer ends of the openings 17 are counterbored at 18 and bosses 19 are provided on the inner side of the front 14 to form parts for effectively holding or carrying the mounting screws. As will be described later, one of the bosses may be employed as part of the stop means for limiting movement of the gripping arms.

20 In practice the general form or shape of the

base 10 may vary widely. However, I prefer to make it in the form of an elongate member or structure generally rectangular in shape, as shown in Fig. 1. I make the base long enough to carry the pivotal mounting means of the arms in the desired spaced relationship and I make the base wide enough or of sufficient vertical extent to give it adequate bearing engagement on the wall W.

The two gripping arms 11 provided by my invention are alike in their general form or configuration but are opposed as shown in Figs. 1 and 2 so that they, in effect, form a pair of jaws which will engage and grip an article such as a cake of soap, as shown in Fig. 5. The pivotal mounting means 12 connects the inner end portions of the arms to the end portions of the base 10. The arms have main or body portions 20 which project outwardly away from the base and inwardly or toward each other from the points of pivotal connection. As will appear from Fig. 2 of the drawings the body portions of the gripping arms are, in effect, diagonally disposed to project from the points of pivotal mounting outwardly and toward each other to carry the tip or gripping portions 22 of the gripping arms at a point spaced forward from the base and so that they oppose each other. In the form of the invention shown in Fig. 1 the gripping portions 22 extend parallel with the base and their ends are bevelled at 23 to form points 24 to engage the article or soap S as shown in Fig. 5. In practice I prefer to form the gripping arms of heavy wire or light bar stock, in which case the body portions are left straight, as shown in the drawings, while the portions 22 are bent to be parallel with the base 10 and are dressed off at 23 to form the points 24.

The pivotal mounting means 12 provided for carrying the gripping arms may be the same for each of the arms. As I have shown in the drawings, the mounting means for each arm 11 involves a spindle 30 projecting inwardly from the inner end of the body portion 20 of the arm to be rotatably carried in a bearing opening 31 in a boss 32 provided on the front 14 of the base 10. The boss 32 may be confined to the front of the base. However, in practice I prefer to provide a boss 33 at the inner side of the base part 14 and I extend the bearing opening 31 through the structure so that the spindle 30 enters the forward end of the boss 32 and extends to the rear end of the boss 33. In practice I proportion the bosses just described so that the bearing opening 31 is long enough to form an effective bearing support for the spindle 30. The spindle 30 is preferably formed integral with the arm.

The means 13 coupling the arms so that they move in synchronism preferably includes lever arms 40 attached to the inner end of the spindles 30 and a link 41 connecting the two lever arms 40. In the preferred construction the inner ends of the spindles 30 terminate flush with the ends 42 of the bosses 33 and are provided with key-like projections 43 which fit correspondingly shaped openings in the arms 40 which are preferably in the form of plates. The key projections 43 fit the openings in the lever arms so that the arms and spindles are keyed together against relative rotation and the key projections are riveted or turned over at 44 so that the arms 40 are retained on the ends of the spindles. Through this construction the arms 40 engage the ends 42 of the bosses 33 to retain the spindles 30 in the bearing openings 31.

The arms are arranged on the spindles so that

the one at one end of the device extends up while the one at the other end of the device extends down and away from said other end of the device, that is, one extends up and out while the other extends down and in, as clearly shown in Fig. 3 of the drawings. The link 41 is pivotally connected to the outer end portions of the two arms 40 and extends in a generally diagonal direction through the cavity 16 in the base. The link connects the arms 40 so that they are coupled to move in opposite directions whenever operated. Through the arms 40 and link 41 when one of the gripping arms 11 is moved about its pivotal support or mounting 12 the other gripping arm is correspondingly moved about its pivotal mounting but in the opposite direction.

To facilitate adjustment of the construction thus far described so that the gripping arms 11 are linked together so that the points 24 will accurately register in a position such as I have shown in Fig. 1, I provide for varying the length of the connecting link 41. In the preferred construction I bend the link intermediate its ends so that the link can be further bent one way or the other to either lengthen or shorten it as between the points where it pivotally connects to the arms 40. In the preferred construction the link 41 is formed of a wire of suitable weight and its ends are turned at 50 to form pins that are rotatably carried in openings in the arms 40. The wire is bent at points 51 intermediate its ends to form a diagonal connecting part 52. In practice a person to adjust the length of the link 41 can grip the diagonal connecting part 52 by means of a suitable tool such as a pair of pliers and by a suitable twisting motion can change the bends 51. Through changing the bends 51, as above described, the link can be readily adjusted, that is, it can be either lengthened or shortened at will.

In practice I provide means for yieldingly urging the gripping arms 11 inwardly or downwardly toward each other to grip an object as shown in Fig. 5. This means is preferably a small or light helical spring 60 having one end connected to one of the bosses 19 and the other end connected to the arm 40 which is adjacent that boss 19. In practice when the device is in operation, as shown in Fig. 5, gravity acting on the gripping arms 11 tends to move them into gripping engagement with the soap S. However, it is desirable to supplement this action by means of the spring 60.

Further, in accordance with my invention I provide for stopping the pivotal movement of the gripping arms under the influence of either gravity or the spring 60. For this purpose I locate the openings 17 and the bosses 19 through which the openings 17 pass somewhat inward or toward the center of the structure from the points where the gripping arms are connected to the base. The boss adjacent the arm 40 that extends downward and inward is located so that that arm engages it and is thus stopped when the gripping arm connected to that arm is in a predetermined position, for instance, in a horizontal position, as shown in Fig. 1. This said arm 40 is shown stopped against the said boss 19 in Fig. 3 of the drawings. When a stop means is provided, as I have just described, the gripping arm in connection with the said arm 40 will be stopped in a given position and the other gripping arm can be adjusted to it by varying the length of the link 41, as above described.

From the foregoing description it will be apparent that I have provided a structure which

is extremely simple and inexpensive of manufacture. The several parts are all simple in form and construction and are such that they can be very easily and quickly assembled and the entire structure, when assembled, can be quickly adjusted to bring the gripping arms into the proper cooperative relationship.

In the form of the invention shown in Figs. 6 to 9, inclusive, the gripping arms 11^a are designed to carry or hold a roll R of toilet paper, or the like. The arms may be similar, generally, to those hereinabove described, although they are proportioned somewhat differently and the tips 22^a are different than those hereinabove described. The tips 22^a are preferably in the form of conical heads applied to the ends of the arms so that the conical parts enter the center or opening 70 of the roll H. In the construction illustrated the tips are shown in the form of small castings applied to the outer end portions 71 of the arms 11^a which arm portions are turned to extend parallel with the base 10. When the conical tips 22^a of the gripping arms enter a roll R, as shown in Fig. 7, the roll is effectively held and the downward pressure exerted by gravity and that created by the spring 60 combine so that the conical tips frictionally engage the roll R holding it against free turning. In practice the parts are related so that the inward movement of the arms is stopped by the ends of the roll R before the pivotal action is stopped as herein-after described so the friction created by gravity acting on the roll is sufficient to hold the roll R against being spun or excessively turned when paper is torn therefrom by a jerking action, and yet is not sufficient to prevent the roll from being turned when a slow pull is applied to the paper to withdraw it from the roll.

In the form of the invention being described if the roll is not in place the pivotal action of the gripping arms is stopped not by one of the lever arms 40 engaging a boss but rather by the arms 40 engaging or stopping against the flange 15 of the base at the ends of the base. In this form of the invention it is desirable to stop the motion of the arms in both directions, the parts being related and proportioned so that one of the arms 40 engages the flange 15 at one end of the base to stop the motion in one direction while the other arm engages the flange at the other end or base to stop the motion in the other direction.

The link 41 which connects the arms 40 may be provided with means for adjustment as above described and, further, I prefer to provide the construction with detent means which serves to yieldingly hold the arms in active position, as shown in Fig. 7 of the drawings. This detent means preferably includes a hump 80 formed on the link 41 to cooperate with a lug 81 projecting inward from the front of the base. The hump 80 is related to the lug 81 so that it passes over the lug as the arms are moved in from a parted position to the active position shown in Fig. 7, the link 41 being sprung somewhat out of normal position as the hump thereon is forced over the lug. This detent means serves to yieldingly retain the gripping arms in the active position and prevent accidental displacement of the roll from the arms in the event that pressure is applied to the roll tending to lift it in a manner that would tend to cause the gripping arms to release it. To release the gripping arms it is necessary to deliberately swing them up and cause the hump 80 to pass over the lug 81.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A holder of the character described including a substantially flat base, a pair of arms pivotally mounted on the base on axes perpendicular to the base, the arms having opposed gripping portions spaced forward of the front of the base, opposed tips on the outer ends of the arms in the form of heads to engage and support a roll of paper, and means connecting the arms for simultaneous opposite operation including levers connected to the arms and a link connecting the levers.
2. A holder of the character described including a substantially flat base, a pair of arms pivotally mounted on the base on axes perpendicular to the base, the arms having opposed gripping portions spaced forward of the front of the base, opposed tips on the outer ends of the arms in the form of conically shaped heads to engage and support a roll of paper, and means connecting the arms including levers connected to the arms and a link connecting the levers.
3. A holder of the character described including a base, a pair of arms pivotally mounted on the base on axes perpendicular to the base, the arms having body portions projecting from the base and opposed gripping portions projecting from the outer ends of the arms, and means connecting the arms including levers connected to the arms, a link connecting the levers, the link being bent intermediate its end to be variable as to length to adjust the relationship of the arms, and a spring normally yieldingly urging one of the levers in a direction to urge the gripping portions toward each other, the axes of the two gripping portions being in a common plane parallel with and forward of the base.
4. A holder of the character described including a base, a pair of arms pivotally mounted on the base on axes perpendicular to the base, the arms having body portions projecting from the base and opposed gripping portions projecting from the outer ends of the arms, and means connecting the arms including levers on the arms, a link having substantially parallel end portions connected to the levers, the link having a connecting portion between the end portions angularly related to the end portions and offsetting the end portions, the connecting portion being variable relative to the end portions to change the length of the link, and an operating spring attached to one of the arms.

MURRAY MARGO.
